UNITED STATES PATENT OFFICE.

HERMAN C. PRIEBE, OF CHICAGO, ILLINOIS.

TANK-CAR.

946,647.

Specification of Letters Patent. Patented Jan. 18, 1910.

Application filed July 21, 1909. Serial No. 508,830.

To all whom it may concern:

Be it known that I, HERMAN C. PRIEBE, a citizen of the United States, residing in Chicago, in the county of Cook and State of Illinois, have invented a new and useful Improvement in Tank-Cars, of which the following is a specification.

My invention has for an object a tank-car construction that shall retain all the requisite 10 resistance to pulling and buffing and twisting strains and yet so lower the center of gravity of a tank-car as to greatly increase its stability and reduce to a minimum the possibility of its being overturned by tilting 15 or by the side-wash of its contents; and the invention has for further objects such other improvements in construction or function as may be found to obtain in the devices herein-after described or claimed.

In the accompanying drawings, forming a part of this specification, and in which like reference numerals indicate like parts in all of the figures, Figure 1 is an end elevation of the car; Fig. 2 is a side elevation of some- 20 what over half the length of the car, with part of the tank-wall broken away, and the sill and bolster construction shown in median longitudinal section; Fig. 3 is a sectional view taken on the line 3—3 of Fig. 2; Fig. 4 is a sectional view taken on the line 4—4 of Fig. 3; Fig. 5 is a sectional view taken on the line 5—5 of Fig. 3; Fig. 6 is a detail of the bolster and sill construction, partly in 25 plan and partly in section at the plane of the top face of the bolster; and Fig. 7 is a fragmentary sectional view horizontally and longitudinally through the middle of the bolster and its junction with the center-sills and draft-sills.

20 is the cylindric tank, whose circumference intermediate the body-bolsters 21 is dropped considerably below the line of draft, each end of the cylinder being segmentally recessed to accommodate the body-bolster 45 and the draft-rigging. The flat horizontal section of tank-bottom roofing such recess, at each end of the car, is formed by the flat plate 22, whose outer end and upturned lateral edges are riveted, respectively, to the 50 inwardly turned lower edge 23 of the tank-end 24 and to the lateral lower edges of the cylindrically bent tank-plate 25, and whose inner edge 26 is extended over and riveted down upon the top-flanges 27 of the I-beam 55 member 28 of the bolster 21, all of these riveted joints being calked oil-tight. The

central transverse or I-beam member 28 of the bolster 21 is solid and imperforate, so as to be adapted to itself form the heading for the segmental end of the middle tank-section, whose circumference is dropped below the line of draft, and this I-beam member of the bolster has integral with it an inwardly extended segment-formed projection 29 that fits within and is calked and riveted, at 30, to the segment of the tank-circumference that is below the plate 22. The plate 22 and bolster 21 thus together close and seal the segmental recess at each end of the tank.

The king-bolt socket 31 is located in the middle of the I-beam member of the bolster, and is additionally supported by the web 32 extending inward over the bolster-projection 29, said web also forming a seat for the 70 ends of the bottom-flanges 33 of the channel-iron center-sills 34, 34. Further inwardly projecting webs 35 and 36 additionally support the bolster-projection 29 and the inner upper flange of the I-beam bolster-member. 75 The aforesaid channel-iron center-sills 34, 34 extend from end to end of the car, to sustain the pulling and buffing strains in the usual manner, but are entirely within the tank, and at each end their lower flanges and the 80 lower part of their webs are cut away to adapt them to be shouldered up against the inner face of the bolster and upon the top face of the plate 22 that roofs the segmental recess of the tank-end. An inwardly projecting member 37, integral with the rest of the bolster-casting, extends and is socketed between the said sills and is strongly riveted to them, at 38, where they shoulder against the bolster, making a rigid connection therewith. A like projection 39, also integral with the rest of the bolster-casting, extends outward and is socketed between the inner 85 ends of the channel-iron draft-sills 40, 40 and is strongly riveted to them, at 41, where 90 they abut against the bolster, making a rigid connection therewith. The ends 42 of the center-sills 34, shouldering upon the plate 22, are rigidly secured to said plate 22 by angle-irons 43, each of which has its vertical 95 flange riveted to the inner face of the web of the adjacent sill and its horizontal flange riveted upon the top face of the plate 22. The upper flanges of the draft-sills support 100 and are riveted to the plate 22, and the ends 110 of said draft-sills are additionally secured to the tank by the end-plate 44, whose lower

part is riveted to the sill-ends and whose upper part is riveted to the tank-end 24. The space between the center-sills 34, 34 is spanned by the longitudinal tie-plate 45, extending their full length and resting and riveted upon the upper flanges of said sills. The tank bottom below the center-sills, intermediate the bolsters, is supported and bracketed to said sills by the plurality of brackets 46, gripping and riveted to the lower flanges and lower part of the webs of said sills. And the said portions of the tank-bottom, below the draft-line and intermediate the bolsters, is additionally supported by the pairs of laterally oblique brace-plates 47, 47, whose lower ends are riveted against the inner face of the tank-bottom, and whose upper ends are riveted upon the tie-plate 45 above the upper flanges of the sills.

It is plain that the foregoing construction provides a tank-car in which the tank is dropped to the lowest possible center of gravity and yet entire rigidity and resistance to both pulling and buffing strains, along the line of draft, are preserved, as well as the essential resistance to lateral and twisting strains that would peculiarly tend to spring the joints of the tank and occasion leakage. This resistance to twisting strains is particularly accomplished by the manner of the rigid connection between the center-sills and body-bolster and draft-sills, and by the full lateral support provided by the flat tank-end bottom resting across the full width of the body-bolster. No material proportion of either the pulling or buffing or twisting strains comes upon the joints of the tank-plates. The portion of the middle of the tank that drops below the line of draft is all utilized for load, the proportion of the load displaced by the interior center-sills and braces being inconsiderable. The flat bottoms at the ends of the tank provide convenient faces to be utilized in jacking up the car-body. The bolster-casting projecting within and calked and riveted to the interior of the portion of the tank-shell that drops below the level of the top face of the bolster, provides a strong support and bracing for the part of the tank-shell that carries the heaviest load, and so peculiarly stiffens and strengthens the shell and prevents the warping and distortion that is one of the most usual causes of leakage in tank-cars. The brace-plates extending from the top flanges of the center-sills to the interior face of the tank bottom, intermediate the bolsters, additionally stiffen the tank-shell and provide that a great part of the load-strain shall be carried where it is most effectively supported, on the top of the web and upper flanges of the center-sills. The bracketing of the dropped portion of the tank-shell, intermediate the bolsters, to the lower flanges

of the center-sills, not only supports said bottom but also provides a considerable free and open space between such bottom and said sills, so that said sills shall not interfere with or impede the free outflow of the tank-contents from the usual outflow port in the middle of the tank-bottom.

My invention is hereinabove set forth as embodied in one particular form of construction, but I do not limit it thereto or to less than all the possible forms in which the said invention as hereinafter claimed may be embodied and distinguished from prior devices for like purposes.

I claim:—

1. In a tank-car, in combination: body-bolster castings; draft-sills secured to said bolsters; a center-sill structure shouldered upon and secured to said bolsters and draft-sills and in the line of draft; and a cylindric tank having its reduced ends supported upon and secured to said bolsters and draft-sills, and having its bottom intermediate said bolsters dropped below said center-sill structure; the ends of such dropped bottom portion of the tank being each headed and sealed by an imperforate section of the corresponding bolster-casting; substantially as specified.

2. In a tank-car, in combination: body-bolster castings; draft-sills secured to outward projections of said bolsters; a center-sill structure shouldered upon and secured to said bolsters and draft-sills and in the line of draft; and a cylindric tank having its reduced ends supported upon and secured to said bolsters and draft-sills, and having its bottom intermediate said bolsters dropped below said center-sill structure; the ends of such dropped bottom portion of the tank being each headed and sealed by an imperforate section of the corresponding bolster-casting; substantially as specified.

3. In a tank-car, in combination: body-bolster castings; draft-sills secured to said bolsters; a center-sill structure shouldered upon and secured to said bolsters and draft-sills and in the line of draft, an inward projection of each bolster being socketed in said center-sill structure; and a cylindric tank having its reduced ends supported upon and secured to said bolsters and draft-sills, and having its bottom intermediate said bolsters dropped below said center-sill structure; the ends of such dropped bottom portion of the tank being each headed and sealed by an imperforate section of the corresponding bolster-casting; substantially as specified.

4. In a tank-car, in combination: body-bolster castings; draft-sills secured to said bolsters; a center-sill structure shouldered upon and secured to said bolsters and draft-sills and in the line of draft, the ends of said center-sill structure being riveted to a plate that is supported upon and secured to said

- draft-sills; and a cylindric tank having its reduced ends supported upon and secured to said bolsters and draft-sills, and having its bottom intermediate said bolsters dropped below said center-sill structure; the ends of such dropped bottom portion of the tank being each headed and sealed by an imperforate section of the corresponding bolster-section; substantially as specified.
5. In a tank-car, in combination: body-bolster castings; draft-sills secured to said bolsters; a center-sill structure shouldered upon and secured to said bolsters and draft-sills and in the line of draft; and a cylindric tank having its reduced ends floored with flat plates supported upon and secured to said bolsters and draft-sills, and having its bottom intermediate said bolsters dropped below said center-sill structure; the ends of such dropped bottom portion of the tank being each headed and sealed by an imperforate section of the corresponding bolster-casting; substantially as specified.
6. In a tank-car, in combination: body-bolster castings; draft-sills secured to said bolsters; a center-sill structure shouldered upon and secured to said bolsters and draft-sills and in the line of draft; and a cylindric tank having its reduced ends supported upon and secured to said bolsters and draft-sills, and having its bottom intermediate said bolsters dropped below said center-sill structure and supported interiorly thereby; the ends of such dropped bottom portion of the tank being each headed and sealed by an imperforate section of the corresponding bolster-casting; substantially as specified.
7. In a tank-car, in combination: body-bolster castings; draft-sills secured to said bolsters; a center-sill structure shouldered upon and secured to said bolsters and draft-sills and in the line of draft; and a cylindric tank having its reduced ends supported upon and secured to said bolsters and draft-sills, and having its bottom intermediate said bolsters dropped below said center-sill structure and bracketed interiorly thereto; the ends of such dropped bottom portion of the tank being each headed and sealed by an imperforate section of the corresponding bolster-casting; substantially as specified.
8. In a tank-car, in combination: body-bolster castings; draft-sills secured to said bolsters; a center-sill structure shouldered upon and secured to said bolsters and draft-sills and in the line of draft; and a cylindric tank having its reduced ends supported upon and secured to said bolsters and draft-sills, and having its bottom intermediate said bolsters dropped below said center-sill structure and bracketed to the basal portion thereof; the ends of such dropped bottom portion of the tank being each headed and sealed by an imperforate section of the corresponding bolster-casting; substantially as specified.
9. In a tank-car, in combination: body-bolster castings; draft-sills secured to said bolsters; a center-sill structure shouldered upon and secured to said bolsters and draft-sills and in the line of draft; and a cylindric tank having its reduced ends supported upon and secured to said bolsters and draft-sills, and having its bottom intermediate said bolsters dropped below said center-sill structure and supported by braces depending from the top thereof; the ends of such dropped bottom portion of the tank being each headed and sealed by an imperforate section of the corresponding bolster-casting; substantially as specified.
10. In a tank-car, in combination: body-bolster castings; draft-sills secured to said bolsters; a center-sill structure shouldered upon and secured to said bolsters and draft-sills and in the line of draft; and a cylindric tank having its reduced ends supported upon and secured to said bolsters and draft-sills, and having its bottom intermediate said bolsters dropped below said center-sill structure; the ends of such dropped bottom portion of the tank being each headed and sealed by an imperforate section of the corresponding bolster-casting, which has a segment-formed projection extending into and securely fitted within such bottom portion of the tank; substantially as specified.
11. In a tank-car, in combination: body-bolster castings; and a cylindric tank having its reduced ends supported upon and secured to said bolsters, and having its bottom intermediate said bolsters dropped below the line of draft; the ends of such dropped bottom portion of the tank being each headed and sealed by an imperforate section of the corresponding bolster-casting; substantially as specified.
12. In a tank-car, in combination: body-bolster castings; and a cylindric tank having its reduced ends supported upon and secured to said bolsters, and having its bottom intermediate said bolsters dropped below the line of draft; the ends of such dropped bottom portion of the tank being circumferentially secured to and laterally supported and stiffened by said body-bolsters; substantially as specified.

In testimony whereof I hereunto set my hand in the presence of two subscribing witnesses.

HERMAN C. PRIEBE.
